SLIDER FOR FASTENERS

Filed June 26, 1930

UNITED STATES PATENT OFFICE

2,042,325

SLIDER FOR FASTENERS

George E. Prentice, Berlin, Conn., assignor to
 G. E. Prentice Manufacturing Company, New
 Britain, Conn., a corporation of Connecticut

Application June 26, 1930, Serial No. 463,930

29 Claims. (Cl. 24—205)

This invention pertains to fastening devices of the class commonly known as separable, or interlocking, fasteners of which the patent to Prentice, No. 1,658,392, February 7, 1928, may be cited as an example. Such fasteners in general comprise complementary series of fastener elements at the opposite sides of the gap which is to be closed, the elements of the opposed series being moved into and out of cooperating relationship by means of a slider having cam-like guides designed for the purpose. When these cam-guides are of such slope and/or radius of curvature as to insure ease of operation, the slider tends to slip and allow the gap to open inadvertently when subjected to strain. Accordingly attempts have been made to provide retaining or locking devices to prevent such accidental movement of the slider. In order to simplify the construction and the operation as much as possible, it has been proposed to associate such locking or retaining means with the usual pull tab which is provided for actuating the slider, and in such constructions it has been common to cause the retaining device to come into action when the pull tab is released by the operator and under the action of gravity hangs downward from its point of support.

However, in some garments or other articles to which such fasteners are applied, the gap is closed by upward movement of the slider, while in others the gap is closed by downward movement of the slider. It is thus necessary, if a slider of this kind is to be of universal utility, that its locking and retaining means be equally effective whether the slider be moved upwardly or downwardly in closing the gap, but this has not ordinarily been the case with sliders having pull actuated locking means, so that garment manufacturers, for example, have commonly been obliged to provide themselves with fasteners of two distinct forms to meet their different requirements.

In accordance with the present invention I provide a double locking slider of universal applicability, but which at the same time is very simple and inexpensive, and which is reliably retained in position after the gap has been closed, whether by upward or downward movement of the slider, the retaining means provided being so associated with the pull tab as to become operative when the pull is released by the operator.

In the accompanying drawing I have illustrated a preferred embodiment of the invention by way of example, and in the drawing:

Fig. 1 is a fragmentary front elevation, to large scale, illustrating a fastener of the type referred to, provided with a slider embodying the present invention and arranged to close the gap by upward movement;

Fig. 2 is a vertical section substantially on the

line 2—2 of Fig. 1, showing the parts positioned to permit movement of the slider longitudinally of the series of fastener elements;

Fig. 3 is a view similar to Fig. 2, but showing the pull tab in depending or locking position.

Fig. 4 is a view similar to Fig. 3, but showing the slider as arranged for closing a gap by downward movement, the pull tab being in the locking position;

Fig. 5 is a side elevation of a rivet or pull retaining device forming a part of the improved slider;

Fig. 6 is a section on line 6—6 of Fig. 5;

Fig. 7 is a composite view showing in side and end elevation the pivot member or shaft which supports the tab;

Fig. 8 is an edge elevation of the pull tab, removed from the slider; and

Figs. 9 and 10 are sectional views, similar respectively to Figs. 3 and 4, of a modified form of slider.

Referring to the drawing and particularly to Fig. 1, the numerals 1 and 2 indicate respectively two flexible stringers or tapes, preferably having beaded or thickened edges, and adapted to support the opposed series 3 and 3^a of fastener elements. These elements are of independent unit type, such for example as shown in the Prentice patent above referred to, but are illustrated merely for the purpose of indicating the utility of the present invention and by way of example of fastener elements of this general type. As is usual, the upper ends of the stringers may be provided with stops 4, and the lower ends may be provided with similar stops, not here shown.

The slider 5 which forms the immediate subject matter of the present invention comprises front and rear wings 6 and 7, respectively, united by a relatively narrow neck portion 8. The wings 6 and 7, and the neck 8 may, if desired, be formed integrally from sheet metal and bent to proper shape, or the body of the fastener comprising the front and rear wings and the neck may be made in any other appropriate way, as for example by die-casting. In the device here shown, members 9 and 10 having curved outer surfaces, project upwardly from the lateral edges of the neck 8, the curved outer surfaces of these members acting as guides to assist the fastener elements 3 and 3^a in entering the converging guide channels provided for them in the body of the slide. The guide channels are of the usual Y-shape, being defined by appropriate flanges or other confining members common to the art.

In order to prevent the front and rear wings 6 and 7 from spreading abnormally, I provide a rivet member 11 preferably of substantially the cross-section shown in Fig. 6, the smaller or tapering edge of the rivet constituting the dividing element

at the junction of the diverging channels within the slider, and the non-circular cross-section of the rivet preventing it from rotating relative to the wings. This rivet member is provided with an 5 enlarged head 12 at its front end, having a shoulder 13 which engages the front face of the wing 6, and the opposite end of the rivet is headed over at 14 against the outer surface of the rear wing 7 thus preventing the wings from spreading apart. 10 The head 12 of the rivet constitutes convenient means for retaining the slider actuating pull, and to this end is provided with a downwardly projecting, somewhat resilient hook portion 15, whose free end 16 is disposed closely adjacent to or in 15 contact with the outer surface of the front wing 6 at a point substantially spaced from the neck 8. The hook member 15 is provided with a recess 17 open toward the front wing thereby to provide a journal opening whose axis extends transversely 20 of the slider and preferably is located substantially midway between the top and bottom of the slider. The pull tab for operating the slider is preferably of substantially T-shape in vertical section, the crossbar of the T constituting the cam portion of 25 the pull as hereinafter described, while the longitudinal part of the T constitutes the finger-engaging portion,—the pivotal axis of the pull preferably being substantially at the intersection of its transverse and longitudinal parts. In the specific 30 embodiment herein illustrated, the pull is provided with a pivot member which is separate from the finger-engaging portion and which consists of the central cylindrical part or shaft 18 which turns in the journal opening or recess 17, and the 35 flattened end portions 19 and 20 which are here shown as of substantially elliptical cross section (Fig. 7). The finger-engaging portion 21 of the pull tab may be made of sheet metal by stamping and bending, or in any other suitable way and of 40 any desired material, and in the embodiment illustrated is furnished with substantially elliptical loop members 22 and 23 spaced to straddle the rivet head. These loop members are elongate in a direction at right angles to the plane of the 45 substantially flat main body or finger engaging portion of the pull tab with their shorter axes substantially in said plane, and are adapted snugly to embrace the opposite ends 19 and 20 of the pivot member, the outer surfaces of these loop 50 members 22 and 23 constituting smoothly rounded cams symmetrical with respect to the plane of the pull tab, as will be described hereinafter. In the arrangement shown in Figs. 1 to 4 inclusive, the front wing 6 is provided with an opening whose 55 opposite ends 32 and 33 are of sufficient size to permit the swinging therethrough of the loop members 22 and 23 in either direction, that is, by a swinging movement of the tab 21 either upwardly or downwardly from the position of Fig. 2. 60 Referring to Fig. 3, the cam loops 22 and 23 when thus swung through the openings are adapted firmly to press the fastener elements 3 and 3^a against the rear wing 7, or conversely to pull, through the intermediary of the rivet member 11, 65 the rear wing firmly against the fastener elements. The shape and position of the cam loops 22 and 23 is, however, such that when the tab 21 extends outwardly from the wings, for instance as in Fig. 2, the slider is free for movement. 70 In assembling the slider, the body of the slider is first formed by bending or otherwise as above described. The ends of the pivot are then fitted into the loops 22 and 23 of the pull tab, and the central part 18 of the pivot is placed within the 75 recess 17 of the rivet head 12. The rivet is then

passed through suitable aligned openings in the front and rear wings 6 and 7 and is riveted over against the outer surface of the rear wing as above described. With the pull device disposed substantially in the slider actuating position shown in 5 Fig. 2, the fastening device may be assembled by threading the slider over the opposed series of fasteners.

In use, when it is desired to move the pull device for closing the gap the pull is swung out to the 10 operative position of Fig. 2, and is used in moving the slider. When the gap is closed, the pull is released or preferably pushed downwardly and rearwardly to the position of Fig. 3, during which operation the cam surfaces of the loops 22 and 23 15 frictionally engage the front faces of the fastener elements 3 so as to create sufficient friction between these elements and the rear wall 7 of the slider body to retain the slider in adjusted position, the slight resiliency of the hook member 20 affording a somewhat yielding abutment which facilitates the operation of the tab and tends to retain the latter in locking position. By swinging the pull tab out toward the horizontal position, the friction is relieved and the slider is free 25 for movement.

Due to the symmetrical shape of the loops 22 and 23, that is to say of the actuating cam surfaces, substantially the same locking or retaining effect is produced whether the pull be swung into 30 the locking position shown in Fig. 3 or into the second locking position shown in Fig. 4, said locking position being 180° or more apart and at opposite sides of the actuating position of the pull. Accordingly, when the slider is used, as in Fig. 4, for 35 closing the gap by downward movement, the release of the pull tab (or preferably the positive movement of the tab into its depending position) results in retaining the slider in adjusted position in the same way as described above. 40

It is thus evident that the slider is of universal applicability, operating in the same way whether applied for closing a gap by upward or downward movement, and yet the double locking slider thus constructed is of the simplest character, requiring 45 but few parts, and these parts are of simple and inexpensive type and easily assembled, so that the cost of this slider, with its double locking action is but little, if any, greater than that of sliders commonly in use. 50

The modified form of slider of Figs. 9 and 10 which is herein specifically claimed is in general similar to the above described embodiment of my invention, but operates to grip the fastener elements 3 between the opposed inner surfaces 55 of the two wings of the slider. Accordingly in this construction, the opening in the front wing of the previously described slider is not utilized, but the front wing 6 is preferably continuous except for the opening necessary to receive the rivet 60 member 11^a corresponding generally to the rivet member 11 of the other form of the device. In the form of device of Figs. 9 and 10, the head 12^a of the rivet member, and the recess 17^a therein are so disposed with respect to the front 65 wing 6 of the slider that the cam elements of the pull tab are adapted to press against the front wing 6, and in either of the positions of Figs. 9 and 10 to spring or flex the front wing 70 6 back toward the wing 7 and against the fastener elements 3, frictionally to clamp the slider in adjusted position. As in the previously described embodiment, swinging the pull tab 21 out toward the horizontal position relieves the friction and enables the slider to move freely. In the 75

form of slider of Figs. 9 and 10, the head 12^a of the rivet member 11^a is provided with a shoulder 13^a corresponding in function to the shoulder 13 of the rivet for the slider of the other figures.

5 While two desirable arrangements have been described as illustrative of the invention, it is to be understood that the invention is not necessarily limited to these particular embodiments as to shape, size, and proportion of parts, and 10 that the substitution of equivalents may be made without departing from the spirit of the invention, and while the specific construction of the pull and its pivot member or shaft herein illustrated and described is desirable for convenience 15 in manufacture, I contemplate the use of a pull tab having the pivot member or shaft thereof formed integrally with the pull member or otherwise constructed within the scope of the appended claims.

20 I claim:

1. A slider for use with fasteners of the kind having stringers carrying series of interengaging fastener elements, said slider having convergent guide channels for the reception of the opposed 25 series of fastener elements, the slider being adapted for alternative use with fasteners which are closed by upward or downward movement of the slider, respectively, and comprising spaced front and rear wings, said slider having a pull 30 for moving the slider lengthwise of the series of fastener elements, the pull being mounted to pivot about an axis extending transversely of the direction of movement of the slider and located substantially midway of the length of the 35 slider, the pull normally depending from its axis toward that end of the slider which for the time being is the lower end, the pull carrying means operative, when the pull extends toward either end of the slider, respectively, to clamp 40 the fastener elements between the wings.

2. A slider for use with fasteners of the kind having stringers carrying series of interengaging fastener elements, said slider having convergent guide channels for the reception of the opposed 45 series of fastener elements, the slider being adapted for alternative use with fasteners which are closed by upward or downward movement of the slider, respectively, and comprising spaced front and rear wings and a pull retaining element, and a pull mounted on said retaining element to pivot about an axis disposed at a substantially fixed distance from one end of the slider so that when not in use for moving the 50 slider the pull may depend from its axis toward that end of the slider which for the time being is its lower end, and means operative by the pull, when the latter is swung to either of approximately opposite sides of its axis toward the series of fastener elements, to cause one wing at 55 least to flex and approach the fastener elements whereby to clamp the slider in adjusted position.

3. A slider for fasteners of the kind having stringers carrying series of interengaging fastener elements, said slider having convergent guide 60 channels for the reception of the opposed series of fastener elements, the slider being adapted for alternative use with fasteners which are closed by upward or downward movement of the slider, respectively, and comprising front and rear wings 65 and a pull retaining member, the wings being spaced to receive the series of fastener elements between them, a T-shaped pull for moving the slider, the pull being mounted to pivot on the retaining member about a definite axis located 70 substantially midway between the top and bot-

tom of the slider and extending transversely of the stringers, the pull normally depending from its axis toward that end of the slider which for the time being is the lower end, and cam means moving in response to movement of the pull about 5 its axis and thereby acting to force one wing of the slider into holding engagement with the series of fastener elements when the pull extends toward either end of the slider.

4. A slider for use with separable fasteners 10 of the kind having opposed series of interengaging fastener elements, said slider having Y-shaped guide channels for the reception of the opposed series of fastener elements and comprising front and rear wings and a rivet secured 15 to one at least of said wings, and means comprising a pull tab supported by the rivet, the pull tab consisting of sheet material having a substantially flat finger engaging portion and cam means disposed adjacent to its pivotal axis, said 20 cam means comprising smoothly rounded transversely elongate surfaces operative alternatively to exert a reactive force between the rivet and one wing of the slider, the cam being so shaped that such force is exerted whenever the tab is 25 moved either upwardly or downwardly into substantially parallel relation to the front wing of the slider thereby forcing said wing toward the rear wing and clamping the fastener elements 30 between the wings to hold the slider in adjusted position.

5. A slider for fasteners of the kind having stringers carrying series of interengaging fastener elements, said slider having convergent guide channels for the reception of the opposed 35 series of fastener elements, the slider being adapted for alternative use with fasteners which are closed by upward or downward movement of the slider, respectively, and comprising guide members spaced to receive the series of fastener 40 elements between them, a pull, and means providing a pivotal axis for said pull, such axis being fixed against movement longitudinally of the front wing, the pull being operative to move the slider longitudinally of the series of fastener elements and normally depending from its pivotal 45 axis toward that end of the slider which for the time being is the lower end, and transversely elongate cam elements having smoothly rounded pressure applying surfaces operative, when 50 the pull is so depending, for causing said guide members to approach and grip the fastener elements between them, thereby to retain the slider in adjusted position irrespective of the direction of movement of the slider necessary to close the 55 fastener.

6. A slider for fasteners of the kind having stringers carrying series of interengaging fastener elements, said slider having convergent guide channels for the reception of the opposed 60 series of fastener elements, the slider being adapted for alternative use with fasteners which are closed by upward or downward movement of the slider, respectively, the slider comprising front and rear wings spaced to receive the series 65 of fastener elements between them, and a substantially T-shaped pull mounted to pivot about a fixed point of the slider, the axis of the pivot being substantially at the intersection of its transverse member with its longitudinal member, the pull normally depending from its pivotal 70 axis toward that end of the slider which for the time being is the lower end, and cam means comprising smoothly rounded pressure applying surfaces operative alternatively to engage the 75

front wing with a line contact and being so associated with the pull device as to cause the wings to approach and grip the fastener elements between them when the pull is in depending position.

5. A slider for fasteners of the kind having stringers carrying series of interengaging fastener elements, said slider having convergent guide channels for the reception of the opposed series of fastener elements, the slider being adapted for alternative use with fasteners which are closed by upward or downward movement of the slider, respectively, and comprising front and rear wings spaced to receive the series of fastener elements between them, a pull, means on the slider providing a pivotal axis for the pull, said axis being at a fixed point of the slider, the pull being movable from slider actuating position to locking position at either side, respectively, of its actuating position, and transversely elongate smoothly rounded cam surfaces associated with the pull for causing the wings to approach and grip the fastener elements between them when the pull is in either of said locking positions.

8. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet having an enlarged head at one end provided with a transverse journal opening, a pivot member journaled in said opening, a pull tab fixed to said pivot member, and cam means symmetrical with reference to the plane of the tab, said cam means comprising transversely elongate smoothly rounded surfaces engageable with the adjacent wing when the tab occupies either of two positions substantially 180° apart, and adapted when so engaging the wing to cause one wing to approach the other wing.

9. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet having a resilient hook portion at one end providing a transverse recess within the bend of the hook, a pivot member disposed in said recess, a pull tab secured to the pivot member, said tab having cam elements symmetrical with respect to the plane of the tab and engageable with the adjacent wing when the tab occupies different predetermined positions, whereby to force one wing toward the other wing.

10. A slider for use with separable fasteners of the kind having opposed series of interengaging fastener elements, said slider having Y-shaped guide channels for the reception of the opposed series of fastener elements and comprising spaced substantially parallel front and rear wings and a relatively narrow neck uniting said wings, a rivet adjacent to said neck, the rivet extending through aligned openings in the front and rear wings, said rivet having heads at opposite ends to prevent the wings from spreading, one of said heads having a hook-like extension whose free end is disposed close to the outer surface of the adjacent wing in opposed relation thereto, and a pull tab having a pivot member disposed within the bend of the hook-like

extension, the pivoted end of the tab having spaced cam means disposed and arranged to engage the adjacent wing and to force the latter toward the opposite wing when the tab is disposed on either side of its pivot and along the 5 adjacent wing.

11. A slider for use with separable fasteners of the kind having opposed series of interengaging fastener elements, said slider having Y-shaped guide channels for the reception of the opposed series of fastener elements and comprising spaced substantially parallel front and rear wings and a relatively narrow neck uniting said wings, a rivet adjacent to said neck, the rivet extending through aligned openings in the front and rear wings, the 10 rivet having elements engageable with the outer faces of the respective wings to limit their separation, a pull tab, a substantially U-shaped hook member at one end of the rivet, the free end of the hook member being opposed to the outer surface of the adjacent wing, thereby to provide a journal opening, the body of the rivet being of non-circular cross section to prevent rotation thereof relative to the wings, the pull tab having a pivot member extending through said journal 15 opening, and substantially symmetrical cam means at the pivoted end of the tab engageable with the adjacent wing to force the latter toward the other wing when the pull tab is disposed on either side of its pivot and substantially parallel to the front wing.

12. A slider for use with separable fasteners of the kind having opposed series of interengaging fastener elements, said slider having convergent guide channels for the reception of the opposed series of fastener elements and comprising spaced front and rear wings, a rivet extending through aligned openings in the front and rear wings, said rivet comprising a single member extending between the wings and having 40 heads at opposite ends to prevent the wings from spreading abnormally, one of said heads being provided with bearing means, and a pull tab having a pivot element journaled in said bearing means, the tab having cam elements projecting 45 from its opposite sides adjacent to its pivoted end, said cam elements being elongate transversely and being respectively engageable with the adjacent wing to force the latter toward the opposite wing when either side of the tab is arranged adjacent to said wing.

13. In a separable fastener of the class described, the combination with flexible stringers carrying spaced interlocking fastener elements, of a fastener operating slider having convergent guide channels for the opposed series of fastener elements and comprising front and rear wings, means providing a journal bearing having its axis transverse to the length of the slider and disposed substantially parallel and adjacent to 60 the outer face of one wing, and a pull tab having pivot means arranged to rock in said bearing, the tab having cam elements projecting from opposite sides thereof near its pivoted end, said cam elements having transversely elongate smoothly 65 rounded surfaces alternatively engageable with the adjacent wing to force the latter toward the opposite wing when either side of the tab is disposed closely adjacent the said wing.

14. In a separable fastener of the class described, the combination with flexible stringers carrying spaced interlocking fastener elements, of a fastener operating slider having convergent guide channels for the opposed series of fastener elements and comprising front and rear wings, 75

means providing a journal bearing having its axis transverse to the length of the slider and disposed substantially parallel and adjacent to the outer face of one wing, and a pull tab having pivot means arranged to rock in said bearing, the tab comprising a main or finger engaging portion and oppositely directed projections adjacent to its pivoted end so that it is of substantially T-shape in longitudinal section, the outer ends of such projections being smoothly rounded, the pivotal axis of the pull being substantially at the intersection of its transverse and finger-engaging portions, said oppositely directed projections constituting cam means respectively engageable with the adjacent wing to force the latter toward the opposite wing when either side of the tab is arranged adjacent to the latter.

15. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet having an enlarged head at one end provided with a transverse journal opening, that part of the rivet which is exposed between the wings tapering in width from its top toward its bottom to constitute a divider element at the junction of the 30 guide channels of the slider, a pivot member journaled in said opening, a pull tab fixed to said pivot member, and cam means symmetrical with reference to the plane of the tab, said cam means being engageable with the adjacent wing when 35 the tab occupies either of two positions substantially 180° apart and being adapted when so engaging the wing to cause one wing to approach the other.

16. A slider for use with separable fasteners of the kind having opposed series of interengageable fastener elements, said slider having convergent guide channels for the reception of the opposed series of fastener elements and comprising front and rear wings spaced to receive a series of fastener elements between them, and a pull device on the slider for moving the latter, said pull device having cam portions so disposed and arranged as to exert frictional pressure against longitudinal faces of the fastener elements when the pull device extends either upwardly or downwardly in substantially parallel relation to the adjacent wing, thereby holding the slider in the desired adjusted position, one of said wings having an opening through which the 55 cam portion of the pull extends for engagement with the fastener elements.

17. A slider, for fasteners of the kind having stringers carrying series of interengaging fastener elements, said slider having convergent guide channels for the reception of the opposed series of fastener elements and comprising front and rear wings spaced to receive the series of fastener elements between them, a pull for actuating the slider, means pivotally securing the pull to the slider, said pull including a cam surface disposed and arranged directly to engage the front surfaces only of the fastener elements with frictional pressure, thereby to exert a camming action to force the fastener elements against the 70 rear wing, the front wing being so shaped as to permit engagement of the cam surface of the pull with the fastener elements.

18. A slider for fasteners of the kind having stringers carrying series of interengaging fastener elements, said slider having convergent

guide channels for the reception of the opposed series of fastener elements and comprising front and rear wings spaced to receive the series of fastener elements between them, the front wing having an opening, a pull pivotally mounted at the front of the slider and having a portion disposed and arranged to extend through said opening, said portion including a cam surface so constructed and arranged as frictionally to engage the front faces of the fastener elements and to 10 press said elements against the rear wing of the slider.

19. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet projecting beyond the outer face of one wing, a pull 20 device pivoted to the projecting end of the rivet, and cam means connected to the pull device and operative when the pull device is disposed at either of approximately opposite sides of its pivot and substantially parallel to the front of the 25 adjacent wing to clamp the fastener elements against at least one of the wings.

20. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet having an enlarged head partly overlying one of the wings, 35 the head having a recess therein, pivot means extending into said recess and retained in said recess by the adjacent wing, a pull tab secured to the pivot means, and cam means connected to the pull tab and operative, when the tab is disposed in either of two positions, substantially 180° apart, to clamp the fastener elements against at 40 least one of the wings.

21. A slider for use with separable fasteners of the kind having opposed series of interengaging fastener elements, said slider having Y-shaped guide channels for the reception of the opposed series of fastener elements and comprising spaced substantially parallel front and rear wings of sheet material, and a relatively narrow neck integrally uniting said wings at one end, a rivet extending through aligned openings in the wings and having at one end a head provided with a hook-like extension whose free end is disposed closely adjacent to the outer face of the adjacent wing in opposed relation thereto at a point substantially midway of the length of the latter, said latter wing having a cam receiving passage therethrough, and a pull tab having a pivot member disposed within the bend of said hook-like head, the pull tab having cam means adjacent to its pivot, said cam means being so shaped and arranged that when the tab is disposed substantially parallel to the adjacent wing, the cam means extends through said passage and frictionally engages the front face of a fastener element or elements and urges said element or elements toward the rear wing.

22. A slider for use with separable fasteners of the kind having opposed series of interengaging fastener elements, said slider having Y-shaped guide channels for the reception of the opposed series of fastener elements and comprising front and rear wings, a rivet passing through aligned openings in the wings, said rivet having an en-

larged head at one end provided with a transverse journal opening, a pivot member journaled in said opening, and a pull tab fixed to said pivot member, the tab having cam elements which are disposed substantially symmetrically with respect to the plane of said tab and which are frictionally engageable with the front faces of the fastener elements when the tab occupies either of two positions substantially 180° apart, and which are adapted when so engaging the fastener elements to force them against the rear wing, the front wing being so shaped as to permit engagement of the cam element with the fastener elements.

15. 23. A slider for use with separable fasteners of the kind having opposed series of interengaging fastener elements, said slider having Y-shaped guide channels for the reception of the opposed series of fastener elements and comprising front 20 and rear wings, a rivet passing through aligned openings in the wings, said rivet having a resilient hook portion at one end providing a transverse recess within the bend of the hook, a pivot member disposed in said recess, a pull tab secured to 25 the pivot member, said tab having cam elements symmetrical with respect to the plane of the tab and engageable with the fastener elements frictionally to retain the slider against movement, the wing next adjacent to the pull having an opening 30 therethrough for the passage of said cam elements.

24. In a fastening of the class described comprising series of interengageable fastening elements, the combination of a slider for engaging 35 and disengaging the fastening elements, the slider having convergent guide channels for the reception of the opposed series of fastener elements, a yieldable support carried by the slider, a pull tab mounted to pivot on the yieldable support about 40 a substantially fixed axis disposed transversely of the rows of fastening elements, and cam means moving in response to swing of the pull tab, said cam means being operable in each of a plurality of different positions of the pull tab for locking 45 the slider in selected position along the rows of fastener elements.

25. A slider for use in engaging and disengaging opposed series of fastener elements by movement longitudinally of said series, said slider 50 having convergent guide channels for the reception of the opposed series of fastener elements, the slider comprising spaced front and rear wings and a connecting neck portion, the front wing having an opening therethrough, a pull-retaining member having a pull-retaining part overlying the opening in the front wing, a pull pivotally engaging said pull-retaining part and arranged to swing about an axis substantially fixed relatively to the length of the slider, said pull 55 having a finger-engaging portion and having cam means adjacent to its pivotal axis, said cam means comprising parts which project substantially symmetrically with reference to the finger-engaging portion of the pull, the respective cam parts being so disposed and arranged that whenever the pull is moved about its axis so as to extend in either direction lengthwise of the series of fastener elements, one of said cam parts extends through the opening in the front wing into 60 frictional engagement with the front faces of the fastener elements, thereby locking the slider in adjusted position.

26. A slider for use with separable fasteners of the kind having opposed series of interengage-

able fastener elements, said slider having Y-shaped guide channels for the reception of the opposed series of fastener elements and comprising spaced substantially parallel front and rear wings of sheet material and a relatively narrow neck integrally uniting said wings at one end, the front wing having an opening therethrough, a pull-retaining element having a portion extending longitudinally of the outer face of the front wing, said portion having a transverse recess, and a pull comprising a finger-engaging portion and a transverse pivot member, said pivot member being disposed within said recess, the pull having cam-like projections adjacent to its pivotal axis, the cam-like projections being substantially symmetrical with respect to the plane of the finger-engaging portion of the pull and being so shaped and arranged that when the finger-engaging portion of the pull is disposed substantially parallel to the adjacent wing one of 20 said cam-like projections extends through the opening in the front wing and frictionally engages the outer face of a fastener element or elements, thereby clamping the slider in adjusted position. 25

27. A slider for fasteners of the kind having stringers carrying series of interengaging fastener elements, said slider having convergent guide channels for the reception of the opposed series of fastener elements and having a body comprising front and rear wings spaced to receive the series of fastener elements between them, a pull for actuating the slider, and pivot means defining a fixed axis about which the pull may swing relative to the slider body, said pull including a cam surface operative to engage the outer surface of one of the fastener elements with frictional pressure, thereby to exert a cam action to force the fastener elements against the rear wing, one of the wings having a passage therethrough 40 to permit engagement of the fastener element by the cam surface of the pull.

28. In a separable fastener of the class described, the combination with flexible stringers carrying spaced interlocking fastener elements, 45 of a fastener operating slider comprising a body portion provided with convergent guide channels for the reception of the opposed series of fastener elements, and an actuating pull comprising a finger-engaging portion and a transverse portion, 50 the opposite ends of said transverse portion constituting alternatively operative slider-locking cams, and pivot means for the pull defining a pivotal axis substantially at the junction of the finger-engaging portion with the transverse portion, said axis being fixed longitudinally of the slider and extending transversely of the latter. 55

29. In a separable fastener of the class described, the combination with flexible stringers carrying spaced interlocking fastener elements, 60 of a fastener operating slider comprising a body portion provided with convergent guide channels for the reception of the opposed series of fastener elements, and a T-shaped actuating pull comprising a finger-engaging portion and a transverse portion, the opposite ends of said transverse portion constituting alternatively operative slider-locking cams, and pivot means for the pull defining a pivotal axis substantially at the junction of the finger-engaging portion with the transverse portion, said axis being fixed longitudinally of the slider and extending transversely of the latter. 70
